UNITED STATES PATENT OFFICE.

WILLIAM O. RICE, OF ROCHESTER, NEW YORK.

HYGIENIC BOTTLE.

1,262,096.

Specification of Letters Patent.

Patented Apr. 9, 1918.

Application filed April 5, 1917. Serial No. 160,051.

To all whom it may concern:

Be it known that I, WILLIAM O. RICE, a citizen of the United States, residing at Rochester, in the county of Monroe and State of New York, have invented certain new and useful Improvements in Hygienic Bottles, of which the following is a specification.

This invention relates to certain new and useful improvements in hygienic bottles.

The primary object of the invention is the provision of a bottle structure that is easy and inexpensive to manufacture the arrangement being such that the interior thereof is easily cleaned and aerated while the device may be formed of any suitable materials such as paper, glass or metal, while the separate members thereof may be each formed of a different material.

A further object of the device is the provision of a bottle construction from which the bottom thereof is removable for readily cleaning the entire interior of the bottle, the bottom being adapted to be normally retained in its closed position by a material that may be readily melted arranged interlockingly between the bottom and the bottle body when in its hardened condition.

With these general objects in view and others that will appear as the nature of the invention is better understood, the same consists in the novel construction, combination and arrangement of parts hereinafter more fully described, illustrated in the accompanying drawing, and then claimed.

In the drawing forming a part of this application and in which like designating characters refer to corresponding parts throughout the several views:—

Figure 1 is a side elevation of the device with the bottom portion thereof shown in central longitudinal section,

Fig. 2 is a view of a bottom portion of a bottle partly in elevation and partly in section, illustrating a slightly different form of the invention,

Fig. 3 is a perspective view of the bottom member illustrated in Fig. 1, and

Fig. 4 is a perspective view of a bottom disk employed with the device.

Referring more in detail to the drawing the device broadly consists of a body portion 10 of the usual milk bottle shape which may be formed of any material such as metal or glass, the structure shown in Fig. 1 being glass, and a cup-shaped base section 11

forming a removable bottom, the said base section being normally maintained upon the body 10 by means of a readily fusible body 12 interposed in interlocking arrangement 60 combining therewith a closure backing or bottom disk 13. The vitreous body 10 being tubular in arrangement has an outwardly projecting annular flange 14 at its open lower end, which end is adapted to be 65 positioned with the flange thereof resting upon the said disk 13 centrally within the base section 11. This base section comprises a bottom 15 having an annular side wall 16 and an inwardly extending top flange 17 70 arranged with a funnel or hopper-shaped rim 18. The device is also adapted to any shape and form of bottle, and designed for holding any commodity.

The base section 11 is preferably formed 75 of pressed metal, such as aluminium or any other suitable material, the disk 13 preferably formed of paraffined paper or pasteboard is flatly arranged within the base section upon the bottom 15 thereof and the 80 glass bottle body 10 seated centrally within the base section upon the disk 13. A suitable form of melted wax is then poured into the funnel rim 18 completely filling the base section 11 surrounding the bottle body 10 85 and sealing the bottom of the bottle and retaining the base section 11 securely upon the bottom portion of said body.

It will be understood that the wax 12 may be placed within the base section in any desirable manner such as by dipping the assembled members into the paraffin or wax, the latter forming a secure seal and lock for the structure. By this arrangement the thorough cleansing of the bottle is made 95 possible by having both ends open for the exposure of air and water when washing the same as well as admitting a brush or scrubbing member therethrough. While the disk 13 and the wax 12 may be 100 readily removed by heating and melting the same so that during the washing operation the disk and wax will rise to the surface of the water and the same may be skimmed off to be sterilized and again employed for use. 105

The gist of the invention resides in the ready interlocking which takes place between the wax 12 and the adjacent wedging faces of the flanges 14 and 17 of the body 10 and base section 11, respectively, as best 110 illustrated in Fig. 1 of the drawing taken together with the simultaneous securing of

the disk 13 which is of substantially the same diameter as the inner sharpened lower edge 19 of the rim 18, the disk and the interior of the body 10 being solely contacted by the 5 contents of the bottle.

If desired, the bottom 15' of the base section 11' may have its central portion cut away as illustrated at 20 in Fig. 2 of the drawing thereby saving material in the formation of the metal base section by lessening the strength of the structure by bringing the weight of the contents of the device onto the paper disk 13', the remaining elements being identical with that illustrated 10 in Fig. 1 and employing the same bottle body 10 and the same amount of wax 12.

The sealing material 12 having a low melting point, the closure bottom for the bottle is readily removed when desired, while 20 the bottom is also easily secured in position by inserting the melted wax and allowing the wax to cool for maintaining the receptacle with the bottom end thereof securely sealed. It will be understood that the upper 25 end or mouth 28 of the bottle structure may be closed in any usual manner, such as by the employment of the usual closure disks, which it is unnecessary to herein illustrate, while the wax completely fills the base section 30 11 outwardly of the body 10. The wax 12 may be removed by setting the bottle upon a heated plate or table, so that the wax will melt and run into some receptacle and the parts being separated can 35 be washed.

What I claim as new is:

1. A device of the class described comprising a tubular body having a projecting bottom flange, a cup-shaped base section 40 within which the bottom portion of said

body is seated, an inwardly projecting flange carried by the base section spaced from the flange of said body, a funnel-shaped rim surrounding the body carried by the inner edge of the base section flange, and sealing means 45 within the said base section in locking engagement between the said flanges.

2. A device of the class described comprising a tubular body having a projecting bottom flange, a cup-shaped base section 50 within which the bottom portion of said body is seated, an inwardly projecting flange carried by the base section spaced from the flange of said body, a funnel-shaped rim surrounding the body carried by 55 the inner edge of the base section flange, sealing means within the said base section in locking engagement between the said flanges, a packing disk of substantially the same diameter as the said rim arranged upon the 60 bottom of said section and between the said bottom and the flange of the tubular body, with the sealing means in contact with said disk and bottom when in its normal hardened condition.

3. A device of the class described having a tubular body having an outwardly projecting base flange, a sheet metal base section provided with a bottom, a disk within said base section with the body seated upon said 70 disk, an inwardly projecting flange upon said base section spaced from the said body flange, a funnel-shaped rim carried by said base section flange surrounding the said body, and fusible wax positioned within said 75 base section in engagement with the said disk and body and filling the base section to the level of the upper edge of said rim.

In testimony whereof I affix my signature.
WILLIAM O. RICE.
